[57] ABSTRACT

A cylindrical body suitable for towing has a support secured to its surface. The support and cylindrical body have parallel axes with the support extending aft a distance beyond the body. Horizontal and vertical fins of a dimension of 30 percent to 40 percent of the lateral cross-sectional area of the body are secured to the aft end of the support. A drop fin having an area of 20 to 30 percent of the vertical lateral area of the body is affixed to the aft end of the body. An increased separation between the center of gravity and center of pressure is effected by the above plurality of fins.

FIG. I

F I G. 2

FIG. 3

DRAG REDUCTION TOWING SYSTEM

STATEMENT OF GOVERNMENT INTEREST

The invention described herein may be manufactured and used by or for the Government of the United States of America for governmental purposes without the payment of any royalties thereon or therefor.

BACKGROUND OF THE INVENTION

The present invention generally relates to the towing of objects in water and more particularly to a system for improving the towing characteristics of towed objects.

The art of towing objects in water probably predates man and all other land animals, back to the time when the fish in the sea were the only living creatures. Since then towing has developed into a science with a multitude of devices and systems.

One such device observed by the inventor consisted merely of adding weights to specified locations. Such a system improves to a small degree the orientation of a towed device. However, many disadvantages emanate from such a practice. These include increased towing line tensions, increased snap loads, increased unit weight, poorer handling capability and excessive vehicle drag.

SUMMARY OF THE INVENTION

Accordingly, it is a general purpose and object of the present invention to provide a device having improved towing characteristics in a liquid medium. It is a further object that the device should be lightweight. Another object is that the device orients itself upon entering the water and remains oriented in the proper direction regardless of changes in position, velocity and/or acceleration of the vehicle doing the towing. An additional object is that if the main body is cylindrical in shape that the device have a separation between the center of gravity and center of pressure in air or from $\frac{3}{4}$ to $1\frac{1}{2}$ diameters of the cross-sectional area of the cylindrical body. Further objects include reduced towing line snap loads, reduced vehicle drag and superior handling capabilities. These and other objects of the invention and the various features and details of construction and operation will become apparent from the specification and drawings.

The above objects are obtained by providing a cylindrical main body with fins and auxiliary components that together provide for the separation of the center of pressure and center of gravity and also provide good flow characteristics for towing through a liquid medium. The size of the fins were determined after extensive experimentation. Portions of the device are easily detachable for ease in handling, storage and transportation and to lessen the chance of damage in handling.

BRIEF DESCRIPTION OF THE DRAWING

FIG. 1 is a perspective view of an embodiment of the present invention;

FIG. 2 is a partial side view showing the tail fin assembly of the embodiment of FIG. 1; and

FIG. 3 is a view of a portion of the hollow detachable slotted tubular tail shaft of FIG. 1 with the horizontal and vertical fins removed.

DESCRIPTION OF THE PREFERRED EMBODIMENT

Maintaining a proper orientation for a towed object is a problem for any towing system. A problem that has been found to exist is the separation between the center of gravity and the center of pressure. As the distance between the two is decreased, the time required for change of orientation of the towed device is decreased.

10 However, this increases the tow line load. Furthermore, the orientation obtained is less stable. Obviously conditions are reversed when the distance between the center of gravity and center of pressure is increased.

15 It has been determined that in a cylinder an optimum separation between the center of gravity and center of pressure is approximately equal to $\frac{3}{4}$ to $1\frac{1}{2}$ diameters of the cylinder for most towing operations.

20 The following device is useful for obtaining the above characteristics and has extensive utility for towed transducer systems. In addition, the teachings are also applicable to any other towed system.

25 Referring now to FIG. 1, there is shown an assembly 10 suitable for towing. The assembly 10 comprises a main body 11 applicable for enclosing a transducer element or other device that may be inserted within. A hemispherical nose cone 12 is bolted to the forward part of body 11. The cone 12 is normally made of a relatively heavy material such as steel. Improved towing characteristics such as reductions in turbulence and drag result from the addition of cone 12.

30 Main body 11 is shown having upper and lower sections 14 and 15, respectively. The sections are for the purpose of inserting and withdrawing equipment. An upper half section of mounting plate 18 is bolted or otherwise affixed to upper section 14. Similarly, a lower half section of mounting plate 20 is affixed to lower section 15.

35 A drop fin assembly 22 is affixed to mounting plate 20. The drop fin assembly 22 comprises a drop fin 24, normally made of aluminum or plastic or other lightweight material suitable for use at sea. The drop fin 24 has been found to work best with cylindrical bodies when the drop fin 24 has an area of 20 to 30 percent 40 of the vertical lateral cross-sectional area of the cylindrical body. The drop fin 24 is affixed to the remainder of assembly 22 by means of an aperture in its upper forward corner so that the fin 24 is free to pivot around this aperture, positioning itself in accordance with the 45 position, velocity and acceleration of the main body 11.

50 Drop fin assembly 22 further comprises a rod support bracket 26 affixed to plate 20 by bolts or other suitable means. The bracket 26 further comprises a pair of flexible extension arms having a hole in their centers. A pair of rod supports 32 in the shape of rollers and having an aperture through their centers in an axial direction are located between and adjacent to the arms of bracket 26 and drop fin 24. A rod 30 is inserted through bracket 26, rod supports 32 and drop fin 24 to hold assembly 22 in place. The rod 30 may be held in place by cotter pins, bolts, flanges or other suitable means to keep it from slipping out of assembly 22.

55 An anti-vortex cone 42 encloses a portion of assembly 22. The drop fin 24 extends through a slot 43 in cone 42. This permits drop fin 24 to move fore and aft freely.

A hollow tubular detachable slotted tail shaft 34, preferably made of aluminum or other lightweight material is located aft of main body 11. A vertical fin having sections 36 and 36a, and a horizontal fin having sections 38 and 38a are inserted in the slotted tail shaft 34 and intermittently welded. Numeral 37 denotes one of a plurality of intermittent welds shown. The vertical fin 36, 36a and the horizontal fin 38, 38a each have an area 30 to 40 percent of the cross-sectional area of body 11.

Shaft 34 is detachably connected to a tubular towing strongback 40 by connecting means 39 which may comprise nuts and bolts or other suitable attaching means.

The towing strongback 40 connects to and extends aft of main cylindrical body 11 for insertion into tubular tail shaft 34. The remaining portion of strongback 40 may be any suitable shape and is affixed to body 11. Strongback 40 has apertures 41 for connection to a towing cable (not shown).

Referring now to FIG. 2, there is shown a side view of the drop fin assembly 22 portion of FIG. 1. The anti-vortex cone 42 is shown that functions mainly as a turbulence reducer to give improved performance during towing. The cone 42 forms a right circular cone with the diameter to height ratio approximately equal.

FIG. 3 shows a portion of the detachable slotted tubular tail shaft 34 with the respective vertical and horizontal fins 36, 36a and 38, 38a removed. The slots 44 are shown separated from each other by a right angle 30 on a plane perpendicular to the shaft's 34 axis.

Prior to towing the above assembly 10 a cable is affixed to an aperture 41 that is closest to the balance point of the assembly 10 in air. On entering the water the drop fin 24 orients the assembly 10 for proper directional attitude.

There has therefore been described an assembly 10 with a basic design for low drag, quick reaction during towing operations. The device with or without the drop fin assembly has utility as a depressor. A depressor 40 tends to orient the towing line in a vertical position bringing the device in close proximity to the ship controlling it. Such a device has quick reaction to the ship's movement.

For towed objects having shapes other than a cylinder, an ideal separation of center of gravity from center of pressure may be determined from a percentage or ratio of cross-sectional area as in the above case.

It will be understood that various changes in the details, materials, steps and arrangement of parts, which have been herein described and illustrated in order to explain the nature of the invention, may be made by those skilled in the art within the principle and scope of the invention as expressed in the appended claims.

What is claimed is:

1. An assembly suitable for being towed in water comprising:
a cylindrical body;
a hemispherical nose cone connected to said cylindri-

cal body;
a towing strongback connected to said cylindrical body and extending aft of said cylindrical body;
a tail assembly connected to said towing strongback, said tail assembly including a vertical fin and a horizontal fin with each of said vertical fin and horizontal fin having an area equal to 30 to 40 percent of the cross-sectional area of said cylindrical body; and

a drop fin assembly connected to said cylindrical body, said drop fin assembly including a drop fin having an area of 20 to 30 percent of the vertical lateral cross-sectional area of said cylindrical body for orienting said cylindrical body in water.

2. An assembly suitable for being towed in water according to claim 1 wherein said tail assembly further comprises:

a hollow detachable tubular slotted tail shaft detachably coupled to said strongback and having slots for insertion of said horizontal and vertical fins.

3. An assembly suitable for being towed in water according to claim 2 wherein said drop fin assembly further comprises:

a rod inserted through said drop fin;
a pair of rod supports adjacent to both sides of said drop fin and having said rod inserted through said supports in an axial direction; and
a rod support bracket connected to said cylindrical body and having a pair of flexible arms with said arms located exterior to said rod supports and having said rod inserted therethrough.

4. An assembly suitable for being towed in water according to claim 3 wherein said towing strongback includes means adapted for connecting a towing cable.

5. An assembly suitable for being towed in water according to claim 1 further comprising:

an anti-vortex cone connected to the rear of said cylindrical body.

6. An assembly suitable for being towed in water according to claim 5 wherein said tail assembly further comprises:

a hollow detachable tubular slotted tail shaft detachably coupled to said strongback and having slots for insertion of said horizontal and vertical fins.

7. An assembly suitable for being towed in water according to claim 6 wherein said drop fin assembly further comprises:

a rod inserted through said drop fin;
a pair of rod supports adjacent to both sides of said drop fin and having said rod inserted through said supports in an axial direction; and
a rod support bracket connected to said cylindrical body and having a pair of flexible arms with said arms located exterior to said rod supports and having said rod inserted therethrough.

8. An assembly suitable for being towed in water according to claim 7 wherein said towing strongback includes means adapted for connecting a towing cable.
